UNITED STATES PATENT OFFICE.

LEWIS F. MILLER, OF FAIRFIELD, OHIO.

POST CONNECTION FOR AEROPLANES.

1,089,144.

Specification of Letters Patent.

Patented Mar. 3, 1914.

Application filed February 26, 1912. Serial No. 680,000.

To all whom it may concern:

Be it known that I, LEWIS F. MILLER, a citizen of the United States, residing at Fairfield, in the county of Greene and State 5 of Ohio, have invented certain new and useful Improvements in Post Connections for Aeroplanes, of which the following is a specification, reference being had therein to the accompanying drawing.

10 This invention relates to post connections for aeroplanes.

The object of the invention is to provide a strong, durable device for connecting the upright posts of a biplane to the frames of 15 the respective planes which will permit the planes to have movement relatively to the posts, as where the planes are warped in controlling the machine; which will permit the posts to be quickly and easily removed 20 and replaced or renewed; which will eliminate or materially reduce the strain and jar imposed upon the planes and stay wires by the jars to which the machine is subjected in alighting and from other causes; which may 25 be manipulated to slacken the wires to enable them to be removed, thus enabling the machine to be dismantled or assembled in a very short space of time; which will maintain the edge of the post substantially in 30 the line of flight but prevent the same from being subjected to any twisting strains due to the relative movement of the planes; and further to provide the stay wires with fastening devices adapted to coöperate with 35 the post connections to enable the machine to be assembled or dismantled quickly and without the use of tools.

In the accompanying drawings, Figure 1 40 is a front elevation, partly in section, of a portion of a biplane showing my invention applied thereto; Fig. 2 is a section taken centrally through one of the connecting devices; and Fig. 3 is a detail of the stay wire fastening device.

45 In these drawings I have illustrated one embodiment of my invention and have shown the same as applied to a biplane of known construction. Inasmuch as the aeroplane as a whole comprises no part of the 50 invention I have only shown so much of the same as is essential to an understanding of the invention. The aeroplane comprises, in the present instance, upper and lower planes 1 and 2, respectively, which are connected 55 one to the other and spaced apart by means of upright posts or struts 3 and the planes

are held against relative displacement by means of stay wires 4. In that type of aeroplane in which the wing tips are warped in controlling the machine the stay wires 60 are used along the front edge and along a portion of the rear edge, but it will be understood that the invention is equally applicable to those portions of the aeroplane which are trussed and those which are free 65 to move.

In order that the posts may be quickly and easily removed and replaced or renewed I have provided a connection, a part of which is adapted to be connected with the 70 post and detachably secured to a fixed part of the connection. In the present arrangement of the connection the fixed part comprises a casting 5 rigidly secured to the frame of the adjacent plane by means of 75 bolts or otherwise. As here shown the casting 5 is connected to the frame by means of eye bolts 6 extending through the casting and through the frame of the plane. The eyes 7 of these bolts are arranged on the 80 inner side of the frame and may be utilized for attaching the stay wires. The detachable part of the connection comprises a socket 8 which is tubular in construction and is adapted to receive the adjacent end of the 85 post 3. This post receiving member or socket is detachably connected with the casting 5 and preferably has movement about an axis arranged in a plane substantially parallel with the frame on which the casting 90 is mounted. In the present embodiment of the invention the casting 5 has a hollow portion or housing 9 provided with a rounded end portion in which is formed an opening 10. This housing forms the socket of a 95 ball and socket joint and is adapted to receive a ball 11 having a stem 12 which extends through the opening 10 in the end of the housing. This stem is detachably connected with the post socket and serves to de- 100 tachably connect the latter with the casting or fixed member 5. This detachable connection is preferably formed by securing to the stem 12 of the ball 11 a collar 13 shaped to fit snugly within the adjacent end of the 105 tubular socket 8. The connections between the collar and the stem 12 and between the collar and the socket 8 may be formed in any suitable manner. In the present instance the stem 12 is screw-threaded into the 110 collar 13 and has its end upset to form a rigid non-rotatable connection between the

two parts. The outer surface of the collar is also screw-threaded and adapted to engage the screw-threaded lower portion of the socket 8, whereby the socket may be 5 readily attached to and detached from the collar 12 and, consequently, the fixed casting 5. To hold the socket 8 normally against displacement a set screw 14 may be provided. To permit the socket 8 to have 10 movement relatively to the casting 5 the upper end of the housing 9 is rounded on a circle described about the axis of the ball 11 and the lower end of the socket member 8 and the collar 13 are concaved to fit snugly 15 upon the rounded end portion of the housing and constitute a bearing surface.

The opening 10 in the end of the housing is flared to permit of the desired amount of movement being imparted to the stem 12 and 20 the socket 8. It will be noted that this connection will permit the socket to have universal movement relatively to the casting and to the frame on which it is mounted. In these main features of construction the 25 sockets at the opposite ends of the posts are substantially similar but in certain details, which I will now proceed to describe, the connections at the opposite ends of the posts differ. For example, the posts employed 30 for this purpose usually have their front sides tapered forwardly so that they will offer the smallest possible resistance to the movement of the aeroplane.

It is desirable that the posts should be so 35 supported that the edge will be maintained in line with the direction of flight. At the same time it is undesirable that the post should be rigidly connected to both planes, as to do so would subject it to a severe twisting strain when the planes were subjected to 40 relative movements. To maintain the post in the desired position and at the same time relieve it of the strain I connect one end of the post to the frame of its plane in such a 45 manner that it is free to move about a vertical axis and to have universal movement about the axis of its pivotal connection to the frame. The other end of the post is so connected to its plane that it has universal 50 movement about the axes of the pivotal connections which are substantially parallel with the frame and has no movement about a vertical axis. This I accomplish by mounting a pin 15 in the ball 11 forming a 55 part of the connection and causing the ends of the pin to project beyond the respective sides of the ball and into vertically elongated openings 16 in the sides of the housing 9. This arrangement will permit the 60 stem of the ball to have a swinging movement relatively to the stem of the casting but will hold it against movement about a vertical axis.

The post sockets are connected to their 65 posts by connecting devices, such as pins 18

and 21 hereinafter referred to, and it will be apparent that in order to remove the post from the aeroplane all that is required is to disconnect the post sockets from the post, as by removing the pins, and then unscrew the sockets from their supporting collars. When this has been accomplished the post can be readily removed and replaced or a new post substituted therefor and this may be accomplished without disconnecting the 70 adjacent posts or the adjacent stay wires. Moreover, this can be accomplished very quickly and very easily without the use of tools.

It is also desirable that some means should be provided to absorb the shock or jar to which the machine is often subjected in making a landing or from other causes. To accomplish this I interpose a cushioning device between the post and one of the connecting devices. As here shown the upper socket is provided on opposite sides with elongated slots 17 through which extends a pin 18 which also extends through an opening in the adjacent end of the post. The pin 18 is 90 removed from the end of the post a distance somewhat less than the distance between the slots and the end of the socket 8 and in the space between the ends of the post and the collar 13 which forms the end wall of the socket I interpose a cushion 19 of suitable resilient material, such as soft rubber. It will be apparent, therefore, that if in landing the lower plane is subjected to a severe jar or shock this shock will be to a great extent absorbed by the cushion 19 and will not be transmitted to the upper plane or the stay wires, thus materially reducing the liability of the breaking of or injury to these parts. The pin 18 may be of any suitable character 105 but, as here shown, it is the ordinary pin having a head at one end and an opening at the other end to receive a cotter pin 20 by means of which it is retained in the proper position.

I also prefer to make the connection between the post and the frame contractible and extensible so that the distance between the planes may be varied and the stay wires slackened or tightened. In the present devices this is accomplished in a very simple manner which consists in connecting one end of the post to one of the post-receiving sockets, preferably the lower one, by means of a pin 21 extending through openings in 115 the opposite sides of the socket and an opening in the end portion of the post 3. The distance between the opening in the post 3 and the end of the post is considerably less than the distance between the opening in the 120 socket and the lower end of the socket. Therefore, when the pin is removed the post will move downward in the socket and thus shorten the distance between the two planes and slacken the stay wires which are con- 125 130 135

nected to the planes at the ends of that post. The wires may be detached and re-attached to the planes and then tightened by moving the post upward relatively to the lower 5 socket 8 until the openings in the two parts are brought into alinement and the pin 8 inserted.

While any suitable means may be employed for connecting the stay wires to the eye bolts I prefer to provide a fastening device which may be readily attached to and detached from the eye bolts 7, thereby eliminating the necessity of twisting the wire each time a connection is made and further 10 enabling the length of the stay wires to be permanently adjusted and this adjustment maintained regardless of the number of times the wire may be detached from the planes. The form of device here shown consists of an open ended link 22, the open end of which is provided with hook-shaped members 23. A link 24 is permanently secured to each end of the stay wire and when it is desired to connect either end of the 15 wire to its plane the link 22 is extended through the eye 7 of the proper bolt and moved until the closed end of the link is in engagement with the eye. The smaller link 24, which is secured to the stay wire, is then 20 inserted through the open end of the link 22 and caused to engage the hook-shaped ends of the link, thus forming a strong durable connection between the stay wire and the eye bolt. To prevent the link 24 from 25 being accidentally displaced from any cause I have shown a spring 25 coiled about the link 22 and having its ends extending through the link, as indicated at 26. That 30 end of the spring adjacent the open end of the link 22 will engage the smaller link 24 and hold the same snugly in engagement with the hook-shaped portions of the link 22, thus preventing accidental displacement 35 of the smaller link. At the same time the stay wire can be very readily removed by merely pressing the spring and disengaging the smaller link from the hook-shaped portion of the larger link.

From the foregoing description it will be 40 apparent that I have provided a post connection for aeroplanes which is at once of a simple, strong and durable character; which will permit of the necessary movements of the plane relatively to the posts; which will 45 permit of the posts being quickly and easily removed and replaced; which may be manipulated to slacken or tighten the stay wires; and which will absorb any shock which may be received by the lower plane 50 and prevent this shock from being transmitted to the upper plane and stay wires.

While I have shown and described one embodiment of the invention it will be understood that the same has been chosen for 55 the purposes of illustration only and that I

do not desire to be limited to the details of construction shown and described, for obvious modifications will occur to a person skilled in the art.

Having thus fully described my invention, 70 what I claim as new and desire to secure by Letters Patent, is:—

1. In a flying machine, the combination, with superposed planes, each plane comprising a frame member, and a post extending 75 between said planes, of a connecting device comprising a base mounted on the frame member of one of said planes between the ends thereof, and a socket removably mounted on said base to receive the adjacent end of 80 said post, the connection between said socket and said post being a slideable one to permit of the ready removal of said socket from said post, whereby said socket may be first detached from said base and removed from 85 said post without altering the positions of said planes.

2. In a flying machine the combination, with superposed planes, each plane comprising a frame member, and a post extending 90 between said planes, of a connecting device comprising a base mounted on the frame member of one of said planes between the ends thereof and a removable socket pivotally mounted on said base on an axis parallel 95 with said plane and adapted to receive the adjacent end of said post, the connection between said socket and said post being a slideable one to permit of the ready removal of said socket from said post, 100 whereby said socket may be first detached from said base and removed from said post without altering the positions of said planes.

3. In a flying machine, the combination, with superposed planes, each plane comprising a frame member, and a post extending between said planes, of a connecting device comprising a base rigidly secured to the frame of one of said planes between the ends thereof, a part pivotally mounted on said 105 base on an axis substantially parallel with said planes, and a post-receiving socket detachably secured to said pivoted part.

4. The combination, with a frame and a post, of a fixed member rigidly secured to said frame, a tubular post-receiving socket, and a supporting member movably mounted on said fixed member, adapted to extend into said post-receiving socket, and having means for detachably connecting said socket to said 115 supporting member.

5. The combination, with a frame and a post, of a fixed member rigidly secured to said frame, a collar pivotally secured to said fixed member and having exterior screw- 125 threads, and a tubular post-receiving socket having screw threads to engage the threads of said collar.

6. A post connection comprising a fixed member having a housing constituting a 130

ball socket and having an opening in the end thereof, a ball mounted in said housing and having a stem extending through said opening, a collar secured to said stem adjacent to the end of said housing, and a tubular socket detachably secured to said collar.

7. A post connection comprising a fixed member having a housing constituting a ball socket and having an opening in the end thereof, a ball mounted in said housing and having a stem extending through said opening, a collar secured to said stem adjacent to the end of said housing, a tubular socket detachably secured to said collar, and means to hold said stem against movement about a longitudinal axis.

8. A post connection comprising a fixed member having a housing constituting a ball socket and having an opening in the end thereof, a ball mounted in said housing and having a stem extending through said opening, a collar secured to said stem adjacent to the end of said housing, a tubular socket detachably secured to said collar, said housing having vertically elongated openings in the side walls thereof, and a pin mounted in said ball, extending into the openings in said housing and having movement therein.

9. In an aeroplane, the combination, with superposed planes, and a post extending between said planes, of a socket secured to one of said planes and adapted to receive the end of said post, that end of said socket which is secured to said frame being closed to limit the movement of said post relatively thereto, said socket having openings in the opposite sides thereof at points remote from the closed end thereof, said post having an opening therein at a point removed from the end thereof a distance less than the distance between the closed end of said socket and the openings therein, and a pin adapted to extend through the openings in said socket and said post when they are moved into alignment.

10. In an aeroplane, the combination, with superposed planes, posts extending between said planes, and stay wires arranged di-

agonally between said posts, of extensible connections between said posts and said planes, and detachable fastening devices for said stay wires each comprising an open link having hooked shaped end portions and a link secured to the adjacent end of the respective stay wire adapted to enter said open link, and engage said hook-shaped end portions, a spring mounted on said open link and having a portion engaging the last-mentioned link to hold the same in engagement with said hook-shaped portions of the opening.

11. In a flying machine, the combination, with superposed planes, and a post extending between said planes, of a post-receiving socket mounted on one of said planes and having pivotal movement relatively thereto, and a cushioning device disposed within the socket between the post and the plane.

12. In an aeroplane, the combination, with superposed planes, and a post extending between said planes, of a socket secured to one of said planes and adapted to receive the adjacent end of said post, a cushioning device supported within said socket, and a sliding connection between said post and said socket.

13. In a flying machine, the combination, with superposed planes, each plane comprising a frame member, and a post extending between said planes, of a device to connect one end of said post to the frame member of the adjacent plane, said device comprising a socket constructed to slide onto and off of the end of said post, and means to detachably connect said socket to said frame member between the ends thereof, said connecting means being constructed and arranged to permit said socket to be detached from said frame member, moved laterally thereto and then slipped off the ends of said post.

In testimony whereof, I affix my signature in presence of two witnesses.

LEWIS F. MILLER.
